(57) **CLAIM**

The ornamental design for a flag finial, as shown and described.

DESCRIPTION

FIG. 1 is an isometric view of a flag finial.

FIG. 2 is a front view of the flag finial of FIG. 1.

FIG. 3 is a back view of the flag finial of FIG. 1.

FIG. 4 is a top view of the flag finial of FIG. 1.

FIG. 5 is a bottom of the flag finial of FIG. 1.

FIG. 6 is a left side view of the flag finial of FIG. 1.

FIG. 7 is a right side view of the flag finial of FIG. 1; and, FIG. 8 is an exploded isometric view of the flag finial of FIG. 1 where the flag finial is connected to a flag and includes magnetic signs.

Portions of FIGS. 1 through 8 are shown in evenly spaced broken lines illustrating portions of the article that form no part of the claimed design. The dash-dot- dash broken lines in the drawings illustrate the boundary of the claimed design, which forms no part thereof. The dash-dot-dot-dash lines in FIG. 8 are directed to environment and form no part of the claimed design.

1 Claim, 6 Drawing Sheets
